Primary Examiner — Susan Moon Lee*(74) Attorney, Agent, or Firm* — Michael G. Johnston; Moore & Van Allen, PLLC(57) **CLAIM**

The ornamental design for a pet tag holder, as shown and described.

DESCRIPTION

FIG. 1 is a top perspective view of a pet tag holder in accordance with my design;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top perspective view of a second embodiment of the pet tag holder;

FIG. 10 is a bottom perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.
